UNITED STATES PATENT OFFICE.

SAMUEL G. CROSSLEY, OF PHILADELPHIA, PENNSYLVANIA.

INTERLOCKING PACKING-SLEEVE FOR ROTARY VALVES.

1,182,630.

Specification of Letters Patent.

Patented May 9, 1916.

Application filed January 24, 1916. Serial No. 73,803.

To all whom it may concern:

Be it known that I, SAMUEL G. CROSSLEY, a citizen of the United States, residing in the city and county of Philadelphia, State 5 of Pennsylvania, have invented a new and useful Interlocking Packing-Sleeve for Rotary Valves, of which the following is a specification.

In a copending application filed by me 10 on the 15th day of September, 1915, Serial No. 50,769, I have described and broadly claimed a rotary valve for internal combustion engines, and my present invention consists of a novel interlocking packing 15 sleeve which is especially adapted to be employed in conjunction with the rotary valve in my aforesaid pending application, although as is apparent, it is not limited to such use, but may be employed in conjunction 20 with any desired type of rotary valve.

With the above in view, my invention consists of a novel construction of a packing sleeve which interlocks with the rotary valve and is provided with a packing ring, 25 and which also serves as a bushing, providing for a uniform bearing and wear, and also preventing leakage between the intake and exhaust ports.

It further consists of a novel interlocking packing sleeve consisting of a series of 30 interlocking split rings, which are connected with the valve in such a manner that the proper expansion and contraction of the packing sleeve is permitted.

It further consists of a novel construction and arrangement of packing sleeve which is made in sections, each section consisting of a split ring having overlapping terminals and provided with ports adapted to register 40 with the ports in the valve, and each section of the packing sleeve is provided at one end with an inwardly extending annular flange adapted to engage the walls of the groove in the valve and to interlock with the juxtaposed end of an adjacent sleeve section.

Other novel features of construction and advantage will hereinafter more clearly appear in the detailed description of my invention.

For the purpose of illustrating my invention, I have shown herein embodiments thereof which are typical of the invention and well illustrate the principle thereof. It is, however, to be understood that these 55 embodiments are typical only and that the various instrumentalities of which my in-

vention consists may be variously arranged and organized and that my invention is not limited to the precise arrangement and organization of these instrumentalities except 60 as set forth in the appended claims.

Figure 1 represents a sectional elevation of an interlocking packing sleeve for rotary valves embodying my invention, and illustrated in conjunction with the valve and 65 valve casing. Fig. 2 represents a perspective view of a portion of the packing sleeve in detached position. Fig. 3 represents a sectional elevation of a portion of the valve and packing sleeve on an enlarged scale. 70 Fig. 4 represents a section on line $x-x$ of Fig. 1. Fig. 5 represents a section on line $y-y$ of Fig. 1. Fig. 6 represents a plan view, illustrating the manner of securing the packing sleeve with respect to the valve. 75 Fig. 7 represents a sectional view of another embodiment of my invention.

Similar numerals of reference indicate corresponding parts in the figures.

Referring to the drawings:—1 designates 80 a valve casing of any desired or conventional type which is shown as being provided with a water jacket 2 having a water inlet 3.

4, 5, 6 and 7 designate, respectively, the 85 explosion chambers which form the upper part of the engine cylinders, as will be understood by those skilled in this art.

8 designates the rotary valve which is provided with an annular groove 9, into 90 which the explosive mixture is introduced from the carburetor in any desired manner, and in the type of valve illustrated, the explosive mixture passes between the fan blades 10 and is forced by them toward opposite ends of the valve. The ends of the valve are mounted on anti-friction bearings 11, and one end of the valve has connected therewith a sprocket wheel 12, which is designed to be connected with the crank shaft 100 of the engine in order to effect the rotation of the valve, as will be understood by those skilled in this art.

13 designates my novel interlocking packing sleeve, which consists of a series of 105 sleeve sections 14, and the split rings 15. The exterior of the valve 8 is recessed to form the annular grooves 16 and the intermediate annular grooves, 17.

A sleeve section 14 is transversely split, 110 as indicated at 18, it being seen that each sleeve section is cut directly across its port

19, said ports being arranged in staggered relation with respect to each other in accordance with the arrangement of the ports in the valve so as to register with the latter.

5 Each sleeve section is provided at one end with an inwardly extending flange 20 and at its opposite end with an inwardly extending flange 21, said flanges forming packing rings which interlock with the grooves in

10 the valve. The flanges 21 are annularly recessed, as at 22, in order to receive the flange 20 of the juxtaposed packing section 14. It will be seen that by such construction, the flange 21 is in engagement with the bottom and side walls of the valve, while the flange 20 adjacent thereto is in engagement with one wall of the groove and the walls of the recess 22. The cut 18 is so situated that all the work in the cylinder has

15 been completed before the port opening registers with a cylinder port. These cuts 18 are formed by angularly cutting through a sleeve to form overlapping tongues 23 and 24, respectively, it being noted that the tongue 24 is at the outer periphery, and since the valve rotates in the direction of the arrow seen in Fig. 4 and Fig. 5, there is no likelihood of the sections of the packing sleeve binding against the walls of the valve

20 casing. Each packing sleeve section is attached to the valve directly opposite its respective port opening with such freedom as to allow for expansion and contraction, and at the same time, the sleeve sections are held

25 in proper relation with respect to the body of the valve, so that their port openings will register at all times with the port openings of the valve. This allows the packing sleeve to have an equal expansion and tension in

30 the valve chamber, it being noted that the valve is supported at both ends on ball-bearings.

In order to illustrate one manner of interlocking the valve sections with the valve,

45 I have shown each valve section as being provided with a plurality of apertures 25 which are of greater diameter than the fastening devices 26, which pass therethrough and are connected with the valve, so that

50 each packing section is permitted to have relative movement with respect to the valve, in both a longitudinal and a circumferential direction. The packing sleeve sections are interlocked in place by means of the split rings 15 which provide for a tight fit and provide at such points the same packing action as is present between juxtaposed ends of the packing sleeve sections. Owing to the novel construction and arrangement of

55 the flanges of the packing sleeve, a tight joint will be formed between the exhaust ports 27 and the intake ports of the cylinder, so that leakage will be prevented through such ports.

60 65 It is also within the scope of my invention

to have the side walls of a packing sleeve section eccentric at their inner periphery, as seen in Fig. 7, the advantage of which is that the free ends of the packing sleeve are more resilient and expand more freely than if the sleeve sections were of uniform thickness throughout. Otherwise, this embodiment of my invention conforms in construction and arrangement to that seen in the other figures of the drawing.

75

When an engine cylinder is under compression and also after the explosion takes place, it will be seen that there is no likelihood of any leakage between the engine cylinder and the valve port, due to the novel construction and arrangement of the packing sleeve and the manner in which it forms a tight joint between such ports at such times. I am thus enabled to hold the compression in the cylinder at all requisite periods. Furthermore, the packing sleeve forms a uniform bearing and serves to automatically take up any wear which takes place within the valve chamber, thereby preventing leakage between the valve ports.

80

85

90

In accordance with my present invention, I employ a packing sleeve which consists of a series of split rings which have the double function of packing the valve and also provides a bushing and bearing for the valve, and since the valve is supported at its ends on anti-friction bearings, it will be apparent that the packing sleeve is free at all times to expand and contract in accordance with conditions met with in practice.

95

It will now be apparent that I have devised a novel and useful interlocking packing sleeve for rotary valves, which embodies the features of advantage enumerated as desirable in the statement of the invention and the above description, and while I have, in the present instance, shown and described typical embodiments thereof which will give in practice satisfactory and reliable results, it is to be understood that the same are susceptible of modification in various particulars without departing from the spirit or scope of the invention or sacrificing any of its advantages.

105

Having thus described my invention, what I claim as new and desire to secure by Letters Patent, is:—

110

1. The combination with a valve having annular grooves therein, of a packing sleeve consisting of split sections having inwardly extending flanges at each end forming packing rings adapted to interlock with the walls of the grooves of the valve, said sleeve forming a bushing for the valve and having juxtaposed flanges of adjacent sections adapted to interlock with each other.

115

2. The combination with a hollow valve having annular grooves on its outer periphery and provided with ports, of a packing sleeve consisting of sections having ports to

120

125

130

register with the ports of the valve and provided with a cut across both sides of the ports and with annular flanges to engage the grooves of the valve, and means to secure the sections to the valve to permit relative movement with respect to the valve to provide for expansion and contraction of the packing sleeve.

3. The combination with a valve having spaced annular grooves and ports to communicate with the ports of the cylinder, of a packing sleeve having inwardly extending flanges at each end, the flanges of adjacent sections being adapted to interlock with each other and with a groove of the valve, said packing sleeve having ports to register with the ports of the valve and having cuts extending across both sides of the port opening, and means to interlock the portions of the sleeve opposite said port opening with the valve.

4. The combination with a valve casing, of a hollow valve mounted therein, and a sectional packing sleeve surrounding the valve and forming a bushing between the valve and the valve casing, said sections having inwardly extending flanges at each end forming packing rings adapted to interlock with the valve, and the juxtaposed flanges of adjacent sections being adapted to interlock with each other.

5. The combination with a valve casing, of a hollow valve within the casing, anti-friction devices on which said valve is mounted, said valve having ports through its periphery and provided with annular grooves on opposite sides of said ports, a packing sleeve surrounding said valve and forming a bushing between the valve and its casing and consisting of sections, each section having at its ends inwardly extending flanges extending into the grooves of the valve, and provided with ports registering with the valve ports and split across the valve ports to form overlapping tongues.

6. The combination with a valve casing having inlet and exhaust ports, of a valve within said casing, a packing sleeve surrounding said valve and consisting of interlocking sections, each of said sections having ports to register with the valve ports, and having a transverse cut on opposite sides of said ports and provided at each end with inwardly extending flanges forming packing rings, each section having opposite its ports an aperture through the wall of the section, and a fastening device of less diameter than the aperture and extending

through such aperture and connected with the section, whereby relative expansion and contraction of the packing sleeve sections and valve is permitted.

7. The combination with a valve casing, of a valve, and a packing sleeve interlocked with the valve and surrounding it to form a bushing between the valve casing and valve, said packing sleeve consisting of sections, each of which is provided at one end with an inwardly extending flange having an annular recess therein and provided at its other end with an inwardly extending flange, the flange at one end of a section interlocking with the adjacent flange recess at the opposite end of the next section.

8. The combination with a valve casing having a centrally located inlet port and provided with cylinder inlet and exhaust ports, of a hollow valve having a centrally located inlet port and provided with outlet ports and with annular grooves on opposite sides of the outlet ports, packing sleeves surrounding the valve and consisting of interlocking sections having at each end inwardly extending flanges forming packing rings which engage the walls of the valve grooves, and single split rings engaging the walls of the valve grooves adjacent the inlet port.

9. A packing sleeve for rotary valves having its outer periphery cylindrical and consisting of sections having ports and split across the ports, each section having at each end inwardly extending flanges forming packing rings, the packing ring at the end of one section being adapted to interlock with the packing ring at the opposite end of another section.

10. A packing sleeve for rotary valves having its outer periphery cylindrical and consisting of sections having ports and split across the ports, each section having at each end inwardly extending flanges forming packing rings, the packing ring at the end of one section being adapted to interlock with the packing ring at the opposite end of another section, and each section having apertures therethrough and located opposite the port.

11. A sectional valve packing sleeve having its outer periphery cylindrical and its inner periphery eccentric, and provided with inwardly extending interlocking flanges forming packing rings.
